UNITED STATES PATENT OFFICE

155,524

DESIGN FOR A COMBINED COVER AND CIGARETTE, CIGAR, AND PIPE REST FOR ASH TRAYS

Edward F. McDonald, Buffalo, N. Y.

Application May 11, 1948, Serial No. 146,286

Term of patent 14 years

(Cl. D85—2)

To all whom it may concern:

Be it known that Edward F. McDonald, citizen of the United States, residing at Buffalo, in the county of Erie and State of New York, has invented a new, original, and ornamental Design for a Combined Cover and Cigarette, Cigar and Pipe Rest for Ash Trays, of which the following is a specification, reference being made to the accompanying drawing, forming a part thereof.

Fig. 1 is a perspective view of a combined cover and cigarette, cigar and pipe rest for ash trays showing the new design; and

Fig. 2 is a side elevation thereof with the right-hand portion broken away and shown in transverse cross-section.

The invention claimed is:

The ornamental design for a combined Cover and Cigarette, Cigar and Pipe Rest for Ash trays, as shown.

EDWARD F. McDONALD.
